CLAIM

The ornamental design for a combined marina power
pedestal and lamp enclosure, as shown and described.

DESCRIPTION

FIG. 1 is a top, front, side perspective view of a com-
bined marina power pedestal and lamp enclosure show-
ing our new design;

FIG. 2 is a front elevational view thereof, the rear being
identical;

FIG. 3 is a side elevational view thereof, the opposite
side being identical;

FIG. 4 is a top plan view thereof on an enlarged scale.

FIG. 1

FIG. 2

FIG. 3
